BOX FORMING MACHINE

Charles E. Palmer, Somers, Conn., assignor to
Package Machinery Company, East Long-
meadow, Mass., a corporation of Massachusetts

Application November 8, 1949, Serial No. 126,189

22 Claims. (Cl. 93—51.1)

1

This invention relates to improvements in a box forming machine, and it is more particularly concerned with a machine for folding pre-scored or creased blanks into box form and adhesively securing the box in its set-up condition.

The main objects of the invention are to provide a machine of the character indicated which is capable of high speed operation, i. e. to convert blanks into boxes at a rate of 100 more per minute; to provide such a machine which may be readily adjusted to operate at various selected speeds within a wide range such as from about 30 boxes per minute to more than 100 per minute; to provide such a machine which may be quickly and easily adjusted to handle blanks and form boxes from such blanks throughout a substantial range of sizes, for example, boxes having a width ranging from as little as 1½ inches to as much as about 10 inches or more, and a length of as little as 3½ inches and up to as long as about 12 inches or more; to provide a machine which is quickly and easily adjustable as to the size of box made mainly by adjusting the positions of various operating elements and replacement of only a few parts of the machine, and to provide a machine of the character indicated which will be efficient and trouble free in operation and durable throughout long periods of continuous operation.

It is a further object of the invention to provide mechanism of the character indicated which may readily be adapted for setting up boxes having single ply side walls and boxes having two ply side walls or two ply end walls or both, or which may have certain of its side or end walls provided with an attached cover forming extension, the other of such walls being either single or double ply.

It is also an object of the invention to provide a machine of the character indicated which can be easily serviced and, in general, it is the object of the invention to provide an improved machine for forming boxes.

Other objects and advantages of the invention will be understood by reference to the following specification and the accompanying drawings (27 sheets) wherein there is illustrated a machine of the character above referred to embodying a preferred form of the invention.

In the drawings,

Figs. 1a and 1b when considered together constitute a side elevation of the machine;

Fig. 2 is an end elevation of the right-hand end of the machine as shown in Fig. 1b;

Fig. 3 is an end elevation of the left-hand end of the machine as shown in Fig. 1a;

Fig. 4 is a longitudinal section as represented by the line 4—4 of Fig. 2, the principal elements of the mechanism being illustrated and certain details being omitted to more clearly illustrate the general arrangement;

Figs. 5 and 6 are plan sections respectively, as

2

represented by the lines 5—5 and 6—6 on Fig. 4;

Fig. 7 is a more or less schematic representation of a pneumatic system employed in the machine;

Fig. 8 is a longitudinal section on line 8—8 of Fig. 5;

Fig. 9 is a cross section on the line 9—9 of Figs. 1a and 5;

Fig. 10 is a sectional illustration corresponding in part to a portion of Fig. 9 but on an enlarged scale;

Fig. 10a is a cross section on the line 10a—10a of Fig. 9 and an end elevation of the right-hand end of Fig. 10;

Fig. 11 is a side elevation of a conveyor structure which appears also in Fig. 1a;

Fig. 12 is a sectional enlargement of a part of the structure appearing in Fig. 11;

Fig. 13 is an elevational enlargement of certain details of structure appearing in Figs. 1a, 1b, 4 and 11;

Fig. 14 is a fragmentary plan section on the line 14—14 of Fig. 13;

Fig. 15 is a fragmentary plan on an enlarged scale of certain details appearing also in Fig. 5;

Fig. 16 is a cross section approximately as indicated by the line 16—16 on Fig. 15;

Fig. 17 is a plan view of a detail as represented by the line 17—17 on Fig. 16;

Fig. 18 is a cross sectional illustration on an enlarged scale of adhesive applying mechanism, another form of which appears in Figs. 1a and 4;

Fig. 19 is a cross section as represented by the lines 19—19 on Figs. 1a and 4;

Fig. 20 is a cross section as represented by the line 20—20 on Figs. 1a, 4 and 5;

Figs. 21 and 22 are vertical and horizontal cross sections indicated respectively by the lines 21—21 and 22—22 on Fig. 1b;

Fig. 23 is a fragmentary view on an enlarged scale corresponding to a portion of Figs. 2 and 21;

Fig. 24 is a section on the line 24—24 of Figs. 5 and 23;

Fig. 25 is a section on the line 25—25 of Fig. 24;

Figs. 26 and 27 are sectional illustrations corresponding respectively to portions of Fig. 4 but showing the structure on an enlarged scale and in greater detail;

Fig. 28 is a sectional view on the line indicated at 28—28 on Fig. 1b but on an enlarged scale;

Figs. 29, 30, 31 and 32 are perspectives more or less diagrammatically, illustrating the steps practiced in the setting up of a box from a blank by the machine, and

Fig. 33 is a perspective illustrating the completed box as discharged from the apparatus shown in Figs. 1 to 28 inclusive.

Fig. 34 is a perspective of a blank for forming another type of box;

Fig. 35 illustrates a box partially formed from the blank of Fig. 34;

3

Fig. 36 is a perspective illustrating the finished box formed from the blank of Fig. 34;

Figs. 37 to 43 inclusive, are views of the mechanism more or less corresponding to certain of the other figures but showing the structure modified to form the box of Fig. 36 from a blank such as shown in Fig. 34.

Fig. 37 is a section generally corresponding to the combination of Figs. 26 and 27;

Fig. 38 is a section on a plane represented by the line 38—38 of Fig. 37;

Fig. 39 is a section corresponding to a portion of Fig. 38 but showing certain parts in a position which they occupy intermediate the two positions of the same parts shown in Fig. 38;

Fig. 40 is a sectional view on the line 40—40 of Figs. 38 and 42;

Fig. 41 is a plan section on the line 41—41 of Fig. 37;

Fig. 42 is a plan section on the line 42—42 of Figs. 37 and 38 but on a smaller scale; and,

Fig. 43 is a more or less diagrammatic representation of the relationship of certain parts and corresponds in part in Fig. 4.

The machine shown in Figs. 1 to 28 inclusive, is designed to convert a flat paper board box blank B such as shown in Fig. 29, into a set-up box such as illustrated in Fig. 33. The blank is pre-cut and scored to provide a central or bottom panel 1, opposite side panels 2—2, tongues 3—3 extending from the opposite ends of the respective side panels 2—2, and end wall panels 4—4.

Blanks of this type are supplied in flat condition to a magazine from which they are withdrawn and fed one by one, the blank being fed edgewise as indicated by the arrow 5. During the edgewise progress of the blank adhesive is applied to the under side of the opposite end wall panels 4—4 in predetermined areas such as represented at 6. The blank moves continuously in the edgewise direction indicated during the application of adhesive to the area 6, such movement being ultimately stopped when the bottom forming panel 1 is located over the path of an upwardly moving mandrel. The mandrel engages the bottom panel 1 and moves the blank upwardly between a pair of side wall folding rollers 7—7 which act to fold the side wall panels 2 downwardly over the mandrel as an incident to the upward movement of the mandrel between the rollers.

Tucking devices comprising rods 8 and tucking fingers 9—9 at the opposite ends of the rods are moved inwardly from opposite sides of the down-turned side wall panels, and are caused to engage and fold the tongues 3 inwardly into the plane of the end walls of the box as indicated in Fig. 31.

During the continued upward progress of the blank, it is moved between oppositely disposed sets of end wall folding rolls 10—10 and 11—11 which act to turn the end wall panels 4 downwardly into engagement with the previously in-turned tabs or tongues 3. The adhesive areas 6 on the under or inner face of the end wall panels 4 register with the respective tongues 3 to effect adhesive attachment of the respective end wall panels to said tongues. The forming of the box is then completed but before the box is stripped from the mandrel and discharged as a finished box, it is carried between opposed pairs of pressure rolls and plates which temporarily hold the adhesively united parts in position to give the adhesive time to set.

4

Referring now to Fig. 4 of the drawings, the machine herein referred to embodies a suitable magazine 12 arranged to support a stack of flat box blanks B in an angular relationship to the horizontal approximately shown. The magazine has its bottom open except for a suitable number of short, in-turned fingers or holders 13 which are sufficient to support the stack of blades but which will nevertheless permit the bottom blank to be pulled face-wise from the magazine. The bottom blank in the magazine is withdrawn facewise by means of a vacuum gripping device comprising vacuum cups 14 carried by a hollow arm structure 15, which is pivoted and rocked about pivots 16 which are suitably supported from a portion of the framework 17 of the machine. The magazine 12 is also suitably supported on the framework 17.

The gripper 15 delivers the blank successively to a horizontal position on the upper reaches of a pair of continuously driven conveyor chains 18—18. These chains are equipped with feeder lugs such as indicated at 19, arranged to engage the rear edges of the successive blanks to feed the same forwardly with the upper reaches of the chains. The blanks are fed forwardly between suitable guides which will presently be described, and between printing roll segments 20 and a platen roller 21 whereby the adhesive is applied to the areas 6 on the under side of the end wall panels of the blanks.

The box blanks are delivered by the feed chains 18 to a position determined by stops 22 which are engaged by the leading edges of the blanks, the blank being thereby positioned with its bottom forming panel overlying the path of travel of a series of mandrels 23 which are carried by a pair of continuously driven chains 24—24. The mandrels are supported between such chains 24—24 by means of cross bars 25 which are suitably secured at their ends to certain links of the chains 24. The chains 24 travel in a clockwise direction as viewed in Fig. 4 about upper and lower shafts 26 and 27. During the downward movement of the mandrels 23 on the right-hand reaches of the chains 24, the completed boxes are stripped from the successive mandrels and deposited on a discharge conveyor 28 which, in turn, delivers the finished boxes to whatever receiving means may be provided.

To facilitate adjustment of the machine to handle various sizes of boxes, the magazine 12 is detachably mounted and readily replaceable by other similar magazines of proper size for holding a given size of box blank. The gripper arm 15 is adjustable in respect of its length and also in respect of the location of its pivot 16. The gripper arm is furthermore easily replaceable in its entirety with other sizes and styles of gripper arms such as may be required for forming certain sizes of boxes.

The conveyor chains 18 are mounted so as to be readily adjustable in the direction of their lengths to position the same, especially the discharge end thereof, with reference to the path of travel of the mandrels 23. The conveyor chains are also adjustable sidewise toward and from each other to adapt them to the feeding of different sizes of blanks. The mandrels 23 are preferably of rigid, one piece construction but they are detachably and replaceably mounted on the chains 24 so that different sizes of mandrels may readily be attached to the chains 24. The side wall folding roll 7 and the sets 10 and 11 of end wall folding rolls are mounted for adjustment

toward and from each other respectively, to properly position said rolls and in folding relation to the sides and ends of the various sizes of mandrels which may be employed in the machine.

The pivots 16 for the gripper comprises oppositely projecting studs which are supported by suitable hangers such as eye bolts 29. These eye bolts have stem portions anchored in horizontal frame portions, the latter being provided with a plurality of holes for that purpose as indicated at 30 (Fig. 4) in any of which holes said hanger bolts may be seated and suitably fastened by upper and lower nuts as indicated.

The pivot studs 16 engage suitably socketed end portions of a rocker member 31 (Fig. 3) which has a centrally located bored boss portion 32. A tubular member 33 is rigidly seated in the bored boss 32 and has its seated end portion provided with a suitable fitting for connecting a suction hose 34 to said tube. Another tube portion 35 is telescopically adjustable in and out of the tube 33 and this tube 35 is provided with diverging branches 36-36. The vacuum cups or grippers 14 are mounted respectively in the free ends of the diverging arms 36 and in the arm or tube 35 adjacent the junction of the arms 36, these grippers being suitably connected to passageways in the arms 36 and tube 35 so that the said grippers may be pneumatically attached to the bottom face of the lowermost blank in the magazine as shown in Fig. 8.

The flexible hose 34 extends from the pipe or tube 33 to a valve 37 (see also Fig. 7) which is connected by means of suitable tubing 38 to a vacuum pump 39 and a vacuum tank 40. The valve 37 is actuated intermittently to establish connection between the vacuum pump 39 and vacuum tank 40 with the suction cups 14, and to intermittently cut off such connection. The valve is, of course, operated in such timed relation that the grippers or suction cups will grip a blank when the gripper is in the elevated position shown in Fig. 8, hold on to the blank during the downward rocking movement of the gripper structure, and then release the blank when it has been transported to a horizontal position on the upper reaches of the feed chains 18. By employing the vacuum tank 40 a uniform and more easily controllable suction is attained at the vacuum cups 14.

The gripper structure is rocked on the axis of its pivot 16 by means of a rotating cam 41 carried by a continuously driven shaft 42 which is journaled in suitable bearings carried by the frame structure. The cam 41 acts against a roller 43 carried by one end of an arm 44 which extends from a rocker 45. The rocker 45 is pivoted at one end on a frame cross member as indicated in Figs. 7 and 8, and at its other end has a depending arm 46. The free end of the arm 46 is bifurcated as shown in Figs. 1a and 8 to adjustably receive one end of a link rod 47 which has its other end pivoted to an arm 48 which depends from the rocker 31 of the blank gripping mechanism.

The cam 41 is operative to rock the arms 44 and 46 and through the link 47 to rock the arm 48 and the gripper mechanism. The cam 41 is, of course, of such size and form that the blank gripper will be rocked through the required predetermined arc of movement and a spring 49 (Figs. 1a and 4) stretched between the arm 46 and a suitable frame portion serves to effect rocking movement of the parts against the action

of the cam 41 and to maintain the cam following roller 43 in contact with the cam 41.

The link 47 is preferably constructed of a central section into which end bearings are threaded so that the effective length of the link may be adjusted by turning the end bearing members in or out of the ends of the central section.

The valve 37 is actuated by means of a valve arm 50 which is pivoted at one end to the body of the valve as indicated at 51, and rocked to actuate a valve pin 52. A spring within the valve body normally tends to urge the valve pin 52 outwardly and to close the valve. When the arm 50 is rocked downwardly or towards the valve body, the pin 52 is depressed and the valve opened. The valve arm 50 has its free end connected to one end of a link 53, the other end of which is pivoted on the free end of a rock arm 54 which is pivoted intermediate its ends as indicated at 55 by a suitable pivot support carried by the frame structure or a bracket portion thereof. The other end of the arm 54 carries a roller which engages the periphery of a rotating cam 56 carried by the continuously driven shaft 42. The cam 56 preferably embodies 2 sections, one of which is rotatably adjustably mounted on the other and the other of which is provided with a hub and adapted to be secured in fixed position on the driving shaft 42. The rotatably adjustably mounted section of the cam 56 may be adjusted relative to the shaft mounted section to extend the circumferential length of the active portion of the cam to thereby maintain the vacuum control valve 37 open for increased periods of time. As shown in Figs. 7 and 8, the two sections of the cam are in registry with each other to hold the vacuum valve 37 open for the minimum period of time which calculations indicate desirable in a structure of the kind described. A spring 54a stretched between the arm 54 and a bracket arm carried by the main frame structure as shown in Fig. 8, serves to maintain the cam follower of the arm 54 in operative engagement with the cam 56.

The conveyor chains 18, 18 are carried by one pair of sprockets on a cross shaft 57 and another pair on another cross shaft 58. The cross shaft 57 is a stationary shaft and the sprockets on that shaft are rotatable thereon whereas the cross shaft 58 is journaled at its ends in suitable bearings. The sprockets on the shaft 58 are keyed to the shaft so as to be rotatable therewith and the shaft 58 is driven to thereby drive the conveyor chains 18.

The cross shafts 57 and 58 are supported on a sub-frame structure having side members 59, on which the shafts 57 and 58 are supported, and transverse interconnecting members 60 and 61 (see Figs. 1a, 5, 8, 11 and 20). This auxiliary or sub-frame structure with the shafts, feed chains, and other parts carried by the frame, is longitudinally slidably mounted on the main frame structure through the agency of a suitable number of brackets such as indicated at 62. These brackets 62 are rigid with the main frame structure and are formed to slidably embrace outer edge portions of the horizontal flanges of said side members 59 which are of angle iron construction as shown.

The conveyor unit comprising the auxiliary frame and the conveyor chains 18, 18 may be adjusted longitudinally and locked in position by means of an adjusting screw 63 (see Fig. 11). The adjusting screw 63 is rotatably mounted at one end on the main frame structure 17 through

the agency of a suitable bearing 64 through which a reduced diameter portion of the screw extends. An enlarged squared end member 65 is attached to the screw for the application of a wrench or adjusting wheel whereby the screw may conveniently be rotated, and said squared member cooperates with the shoulder of the screw on the other side of the bearing 64 to anchor the screw against longitudinal movement.

The screw 63 threadedly engages a sleeve 66 which is anchored in a pillow block 67 that depends from the cross member 60 of the conveyor frame. It will be seen that by rotating the screw 63 the pillow block 67 and the conveyor structure will be caused to travel along the screw to thereby adjust the longitudinal position of the conveyor structure.

The conveyor sprockets 68 on the shaft 57 are held in position on the shaft 57 between the arms 69 and 70 of brackets 71, 71 which are provided for supporting certain guide bars which will presently be described.

The forked arms 69 and 70 of the respective brackets are suitably bored to fit on the shaft 57, the arms 69 being split as indicated in Fig. 8, and provided with clamping screws 72 to permit such arms to be clamped tightly in place on the shaft 57. By loosening the clamping screws 72 the brackets 71 may be adjusted lengthwise of the shaft 57 to correspondingly adjust the positions of the conveyor chain sprockets 68, the screws 72 being then again tightened to lock the parts in the selected position of adjustment.

The conveyor chain sprockets 73 on the shaft 58 may be locked in position on the shaft by means of set screws or the like indicated at 74 (Fig. 19), and these sprockets may accordingly be adjusted lengthwise of the shaft 58 by loosening the set screws 74 to permit adjustment of the sprockets and then resetting the set screws.

The upper reaches of the chains 18, 18 are supported against sagging by means of guides or supports 75, 75. At one end the guides or supports 75, 75 are supported on the shaft 57 through the agency of the brackets 71 which have stud-like projections 76 (see Fig. 8) which telescopically receive suitable socket formations 77 on the adjacent end portions of said chain guides 75. Suitable set screws or keys may be provided if desired, to prevent rotary movement of the sockets 77 and the guides 75 about said stud-shafts 76.

At the opposite or delivery end, the chain guides 75 are supported by attachment to brackets such as indicated at 78, which have end portions fitted on the shaft 58 immediately outside of the respective sprockets 73 in such a manner that the shaft may freely rotate in said brackets. Outwardly of the respective brackets, collars 79 are secured to the shaft 58 so as to hold the brackets and chain guides in proper position relative to the chains. These collars 79 may be fastened by set screws or the like as indicated in Fig. 19.

By reference to Figs. 8 and 11, it will be seen that the conveyor chains 18 are arranged to slant downwardly slightly from their receiving ends to their discharge ends. The carton blanks are, however, supported for substantially horizontal travel by means of the carton blank guides 80, 80 which are disposed immediately outside of the path of travel of the respective chains and supported by attachment to the chain supporting members 75 by suitable bolt means as indicated at 81, and spacer blocks or collars 82.

The downward inclination of the chains 18, 18 serves to cause the carton blank pushers 19 to pull downwardly on the trailing edge of the blank thereby to maintain the blank down against the guides.

Intermediate portions of the carton blank are supported by the guides 80, 80 and the central portion is supported by a normally stationary guide 83 which comprises a tubular section 83a and a rod section 83b which telescopes into said section 83a. The tubular section 83a is normally fixedly supported by means of a depending post 84 which is rigid with the tubular section, said post being anchored to a suitable bracket 85 (see Figs. 5, 8 and 9) which is secured to a cross member of the frame structure 17.

The member 83b is similarly supported by means of a depending post 86 which is rigid with the rod 83b and provided at its lower end with an enlargement or block 87 slidably mounted on a guide rod 88 supported in said auxiliary frame structure.

For some purposes, the section 83b of the central guide may be extended or retracted to alter the position of the delivery end of the support which carries a cross member 89 having upturned end portions 90, 90 as shown in Fig. 20. These upturned end portions 90, 90 are provided to support the carton blank at the proper elevation particularly under a pair of resiliently depressed friction stops 91, 91 (Figs. 8 and 20) against which the leading edges of the carton blanks engage to be thereby retarded, if need be, into contact with the feeding fingers 19 of the conveyor chains so as to avoid premature delivery of the blanks into the zone of operation of the folding devices. The retarding members 91 are slidably mounted on a transverse bar 92 so as to be adjustable crosswise on the machine for adjustment to the most advantageous operating position in reference to the various sizes of cartons which may be formed on the machine.

The bar 92 is mounted for adjustment lengthwise of the conveyor structure by being provided with slotted end formations 93, 93 (Fig. 20) which slidably fit on suitable guide bars 94 mounted on the auxiliary frame side members 59 as best shown in Figs. 11 and 20.

The side margins of the carton blanks are supported during their travel along the conveyor structure by means of side guides which have portions underlying the margins of the blanks and other portions for guiding the side edges of the blank.

At the receiving end of the conveyor structure the side guides consist of bottom members 95 and upper or side members 96, these members extending about one-half the length of the conveyor structure and being disposed in the zone in which the blanks are initially deposited on the conveyor structure as shown in Fig. 5.

These side guides are mounted on lengthwise extending supporting bars 97 which are respectively secured to inverted pillow blocks 98 which are equipped with sleeves 99 having internally threaded end portions such as 99a (Fig. 10) which engage respectively, right and left-hand screw-threading 100 on the opposite ends of a cross shaft 101 (Fig. 9). The shaft 101 is journaled at its ends in suitable bearings 102 which are supported by the main frame structure and this shaft is adapted to be manually rotated by means of a wrench or hand wheel applied to a squared end 103 of the shaft. The sleeves 99 are clamped or otherwise locked in place against lon-

itudinal and rotary movement in the said pillow blocks 98 which depend from the side bars 97. By rotating the shaft 101 the side guides may be adjusted toward or from each other crosswise of the machine. The sleeve 99 has an enlarged split end portion 99b which, by means of a hand screw 99c, may be clamped tight on the screw 100 to lock the same against rotary movement.

The receiving side guide portions 95 and 96 are extended to the delivery end of the machine by means of similar bottom and side guide elements 104 and 105 respectively, these elements being also mounted on portions of the longitudinally extending supporting bars 97. These bars are supported near one end as already explained and as shown in Fig. 9 of the drawings, and at the delivery end of the conveyor they are supported on the upper endes of pairs of posts 106, 106 (see Figs. 1a and 1b, 5 and 20).

The pairs of posts 106 each extend upwardly from cross arms such as indicated at 107, which are carried by inverted pillow blocks 108 which are equipped with longitudinally threaded sleeves or nuts 109 which threadedly engage right and left-hand screw threading on a cross shaft 110. The shaft 110 is suitably journaled at its ends in bearings carried by the main frame structure. By rotating the shaft 110, the marginal guide portions 104 and 105 may be adjusted toward and from each other.

The shaft 110 is operatively connected to the shaft 101 by means of an endless chain 111 and suitable sprockets mounted on the respective shafts. Hence, when the shaft 101 is manually rotated, the shaft 110 will be simultaneously rotated so as to cause uniform adjustment of the entire lengths of the respective side guide structures.

The adhesive applying mechanism comprises a hopper or tank 112 for containing a supply of adhesive in liquid form. This hopper is removably mounted in the apparatus by being seated on a pair of transversely extending cross bars 113, 113 (see Figs. 1a and 19) which are supported at the desired elevation by means of upstanding posts 114, 114 at one end and posts 115 at the other end. The posts 114 are substantially rigidly secured to a part of the main frame structure but the posts 115 are carried by a base element 116 which is vertically, adjustably mounted on the main frame structure so that the supporting bars 113 may be adjusted vertically for a purpose which will presently appear. The base 116 is held in upwardly spaced relation to portions of the main frame 17 by means of set screws 117, 117 while bolts 118, 118 are employed to hold the member 116 down to the position determined by the set screws 117.

The hopper 113 contains a pair of adhesive carrying rollers 119, 119 which are mounted on a shaft 120 that is journaled in bearings carried by the end wall portions of the hopper. The shaft 120 is extended beyond one end of the hopper and is provided with a gear 121 which meshes with and is driven by a pinion gear 122 that is carried by a shaft 123 journaled in bearings carried by the vertically adjustable base element 116. By driving the shaft 123, the adhesive pick-up rolls 119 will be rotated in the path 124 of adhesive contained in the hopper so as to be thereby caused to carry a film of adhesive upwardly for transfer to the printing faces of the

printing segments 20 (Fig. 18), there being one such doctor blade for each roll 119. The doctor blades 125 are each carried by a shaft 126, one of which enters the hopper from each end of the same and is journaled in a centrally disposed bearing 126a and in the end wall of the hopper through which it passes.

Laterally extending elements 127 are secured to the respective doctor blades in position to act on the end walls of the respective rolls 119 thereby to prevent said end walls from carrying an excessive supply of adhesive upwardly adjacent the active surface of the respective rolls. The doctor blades 125 are normally spring-urged toward the cylindrical surfaces of the pick-up rolls 119 by tension springs such as indicated at 128, which are stretched between anchoring pins on the ends of the hopper and anchoring pins projecting from arms 129 which are secured to projecting portions of the shaft 126.

Stop screws such as 130, threaded through lugs extending from the arms 129 and engageable with stop pins such as 131, carried by the ends of the hopper serve to limit the approach of the doctor blades 125 to the pick-up rolls 119. The arms 129 are extended to provide hand levers 132 to facilitate manual rocking of the doctor blade from its operative position as shown in Fig. 18, to an inoperative position clear of the respective rollers 119, the inoperative position being determined by engagement of a stop shoulder 133 on an arm 129 with a portion of a stop member 131.

The arrangement of the spring 128 is such that when the doctor blade is rocked to an inoperative position as indicated, the spring will cross over the center of rotation and become effective to yieldingly hold the doctor blade in said inoperative position.

When the printing segments 20 are out of contact with the adhesive pick-up rolls 119, the adhesive containing hopper may be withdrawn endwise as a unit from the structure by being slid along the supporting bars 113 toward the right as viewed in Fig. 19.

To facilitate handling of the hopper, it is equipped with endwise projecting handles 134, 134 and a supporting bracket 135 is rigidly mounted on the frame for supporting the weight of the inner end portion of the hopper as it leaves the rails 113. When the hopper is withdrawn to a position in which its inner end rests on the bracket 135, it is sufficiently accessible that an attendant can pick up the hopper by the handles at the opposite ends of the hopper.

To lock the hopper in place, its side walls which embrace the supporting rails 113 are provided with notches 136 (Fig. 19) which receive pins 137 which project from the respective rails 113. At the opposite or outer end of the hopper, it is provided with a pivoted bolt and nut structure 138 which cooperates with a notched end portion 139 of one of the rails 113 (see Figs. 19 and 1a) to lock the hopper in place.

To remove the hopper, the nut of the locking device is loosened so as to permit the eye bolt to slide freely out of the notched bar end 139.

As shown in Figs. 19 and 1a, the adhesive-containing hopper is arranged for the utilization of normally cold adhesive. In instances where heated adhesive is desired or, for example, thermoplastic adhesive, the bars 113 are replaced by a heater plate 140 (Fig. 18) which contains electrical heating elements 141, 141 of any suitable character.

The printing segments 20 are detachably

75 The thickness of the film of adhesive carried upwardly by the rolls 119 may be adjusted to suit requirements of each particular case by means of suitable doctor blades such as indi-

mounted on the shaft by means of hub members 142 which are split and provided with clamping screws 143 whereby these hubs and the printing segments carried thereby may readily be adjusted to various positions along the length of the shaft 42. These hubs 142 support the printing segments 20 which have web portions 144 provided with inner ends recessed as indicated at 145 to fit around a portion of the circumference of the shaft 42.

The webs 144 are also provided with arcuate slots 146 in their faces for receiving correspondingly formed, laterally projecting ribs on the hub members 142. The slotted portions of the webs 144 are further slotted as indicated at 147 (Fig. 16) to receive a fastening bolt 148 which is carried by the hub member 142. It will be seen that the web member 144 is circumferentially adjustable relative to the hub member 142, and capable of being fixedly locked in the selected position of adjustment by means of the clamping bolt 148.

The printing surface of each printing unit preferably consists of a rubber or other suitable pad 149 which may be adhesively secured to suitable cylindrical face portions 150 of the respective printing segments. Suitable clips 151 are also preferably employed for anchoring the leading and trailing end portions of the printing parts to the segment 144. These printing pads 149 are advantageously in the form of intaglio printing plates provided with a series of pockets 152, 152 which are adapted to pick up a supply of adhesive from the rollers 119 and to transfer such supply to the box blank as the latter passes under the platen rolls 21.

This intaglio printing rubber cushion is capable of yielding under pressure so that extremely accurate adjustment of the printing surfaces to the path of the box blanks is not required. However, by the employment of the intaglio form of printing segments substantially the entire measured amount of adhesive carried by the printing pads will be applied to the box blank regardless of the amount of pressure between the printing segments and the box blank. Furthermore, in the application of adhesive to box blanks the amount of adhesive applied is not usually highly critical so that it is not necessary to provide for minute adjustment of the printing segment position relative to the path of the box blanks.

For supporting or backing up the box blanks during the adhesive applying operation, the platen rolls 21 are provided on a shaft 153 which is freely rotatably journaled in arms 154, 154 adjacent the opposite sides of the main frame structure. These arms 154 are mounted on a cross shaft 155 which is journaled at its ends in bearings 156 that are carried by the main frame structure (see Figs. 5, 15, 16 and 19).

One of the arms 154 is normally secured in fixed position on the shaft 155 by a set screw or other equivalent means. The other arm 154 is secured to said shaft 155 through the agency of an arm 157 which is pinned to the shaft 155 as indicated at 158 (Fig. 15), the free end of the arm 157 having a laterally projecting pin 159 which projects through a hole in the arm 154. A thumb screw 160 threaded through the hub of the arm 154 is provided for locking the arm 154 in assembled relation to the arm 157 with the pin 158 projecting through the arm 154. By this arrangement the platen roller shaft 154 may be raised uniformly across the width of the machine by lifting either arm 154. This facilitates

adjustment of the platen rolls to an inoperative position when desired for cleaning or other purposes, and it also facilitates upward adjustment of said rolls to a position in which the printing segments cannot apply adhesive to the platen rolls in the event that there is no blank in place to receive the adhesive.

Coiled tension springs such as indicated at 161, stretched between a suitable anchor on the main frame structure and a finger 162 carried by the arm 154 serves to normally yieldingly urge the platen rollers to move toward the printing segments. Such movement of the platen rollers is, however, limited by means of a suitable stop screw or pin 163 which projects downwardly from a suitable lug or boss 164 formed integrally with the arm 154. Said stop pin 163 is adjustable in respect of the extent to which it projects from the lug 164 to thereby permit adjustment of the extent to which the platen rolls 21 may approach the printing segments.

The platen rolls 21 are preferably made from a series of alternately arranged large and small discs clamped between collars 165, 165 on the shaft 153. The collars 165 are adapted to be held in place by suitable set screws or the like, so that the position of the platen roll may readily be adjusted inwardly or outwardly along the length of the shaft 153.

When the length of the platen roll has to be changed, the thumb screw 160 is loosened whereupon the arm 154 may be slid outwardly on the adjacent end portion of the shaft 155 and thereby withdrawn from the end of the shaft 153. The shaft 153 with its platen rolls may then be withdrawn endwise from the opposite arm 154. Hence, the platen roll structure may very expeditiously be removed from the machine for changing of the platen rolls. In some instances it is advantageous to equip the machine with a series of different platen roll shafts which may be substituted for one another instead of adjusting or modifying the roll on a single shaft. Such substitution is facilitated by the described arrangement.

For holding the platen roll structure in elevated or inoperative position, there is provided a lever 166 which is pivoted intermediate its ends as indicated at 167 on the frame 17. Stop pins 168 projecting upwardly from the frame 117 serve to determine the limits of movement of the lever 166 about its pivot 167.

A spring 169 normally urges the lever to rock counterclockwise as viewed in Fig. 15, to cause the inner end portion of the lever to assume a position under the stop pin 163. When the lever assumes the dotted line position shown in Fig. 15, the stop pin 163 will come to rest on the lever so that the platen roll will accordingly be held on elevated position. The spring 169 normally urges the lever to rock into engagement with the side of the stop pin 163 so that an attendant of the machine need only lift the platen rolls slightly above their normal position whereupon the lever will automatically move into operative position as indicated in dotted lines in Fig. 15.

Referring again to Fig. 19, it will be observed that the height of the adhesive applying rolls 119 is determined by the height of the supporting bars 113. The position of these bars is determined by adjustment of the posts 114 at one end up or down relative to the frame 17. At the other end, the elevation may be determined by adjustment of the base structure 116 up or down relative to the supporting frame structure. Inas-

much as this vertically adjustable base 116 also carries the pinion 122 whereby the adhesive pick-up rolls 119 are rotated, it will be seen that the operative relationship between the gear 121 and side pinion will not be altered incident to raising or lowering of the adjacent end of the adhesive hopper by the means described.

Leveling of the adhesive container or, in other words, adjustment of the adhesive pick-up rolls 119 into proper operative relationship to the printing segments is accordingly readily accomplished.

Travel of the carton blanks through the adhesive applying zone is additionally controlled by a series of overlying guide rods 170. These guide rods are supported from a sleeve 171 on the shaft 155, the sleeve being held against rotation by a suitable bracket and clamp arrangement carried by the main frame structure and indicated at 172 in Fig. 5.

Brackets 173 are clamped in selected position on the sleeve 171 by means of thumb screws 174 and these brackets have ears 175 which slidably receive posts 176 which extend upwardly from the respective guide rods 170. Downward movement of the posts and guide rods is limited by a suitable nut or stop collar 177 applied to the upper end of each post 176, and a coil spring such as indicated at 178 around each post 176 and between the ears 175 and bosses formed on the rods 170, serve to yieldingly urge the guide rods downwardly to the position determined by the collars 177.

The various operating elements thus far described are driven by means of an electric motor 179 (Figs. 1a and 3) through a belt 180 which engages a pulley 181 on a main shaft 182. This shaft 182 includes a suitable clutch structure 183 which is manually controlled by a hand lever 184. The clutch controlled portion of the shaft 182 carries sprocket wheels 185 and 186 and a pair of pulleys 187 and 188. The pulley 187 acts through a V-belt 189 to drive the pulley 190 of the vacuum pump 39.

The sprocket 186 operates through a chain 191 to drive a sprocket 192 on the shaft 193 of the adhesive-applying mechanism (see Figs. 4 and 19) to thereby effect rotation of the adhesive supply rolls 119. The sprocket 185 acts through a chain 194 to drive a sprocket 195 on a shaft 196 (Fig. 4) which is suitably journaled in the frame structure of the box forming section of the machine. The shaft 196 is also equipped with a sprocket 197 which drives a chain 198 and said chain is threaded around a sprocket 199 on the shaft 42, a sprocket 200 on the shaft 57 of a conveyor, and around a tension adjusting sprocket 201. It will be seen that the chain 198 actuates the printing segments 20 and the cams 41 and 58 and also the conveyor chains 18.

The idler sprocket 201 is carried by one end of a lever 202 which is pivoted intermediate its ends as indicated at 203 in a clamping block 204 which is mounted on the conveyor frame structure cross member 61 (see Fig. 13). Said lever 202 has a handle portion 205 for facilitating manual rocking of the lever and corresponding movement of the idler sprocket 201 to take up or pay out the driving chain 196. The working position of the tensioning sprocket 201 may be fixed by tightening the clamping block 204 on the pivot shaft 203 of the lever through the agency of the clamping screw 206.

When the conveyor structure is adjusted longitudinally to adapt the mechanism to handle dif-

ferent sizes of box blanks, it is advantageous to lock the chains 18 and the driving chain 198 in relatively fixed position in order that the timing of the box blank feeding fingers 19 relative to the positions of the mandrels be maintained. For that purpose there is provided a pair of clamping arms 207 pivotally mounted on a part of the conveyor frame structure and having free end portions embracing the conveyor shaft 58. A clamping bolt and nut arrangement 208 is provided for drawing the clamping arms 207 together to grip and hold the conveyor shaft 58 against rotation, a suitable spring 209 being provided between the arms to normally urge the arms apart when the screw and nut structure is released.

When adjustment is to be made of the longitudinal position of the feed structure, the shaft 58 is initially locked against rotation whereupon the feed structure is moved as desired. The idler sprocket 201 is adjusted to take up or pay out whatever amount of driving chain 198 is required by the adjustment of the position of the conveyor structure, the chain material taken up or paid out being taken up or paid to that portion of the driving chain structure which extends downwardly and around the driving sprocket 197. It is found that as a practical matter this arrangement avoids alteration of the timing of the feed chains 18 relative to the other operating parts of the mechanism.

From the foregoing explanation of the box blank feeding mechanism, it will be seen that the feeding conveyor structure is adjustable both in respect of the position of its delivery end from which the blanks are discharged to the box forming mechanism, and in respect to the spacing of the feed chains relative to each other and in respect of the position of the various lengthwise extending guides whereby various sizes of carton blanks may be efficiently handled. The principal adjustments are effected by merely turning the shaft 104 and the adjusting screw 63. Other of the parts, such as the individual overlying guides 170, the position of the chains, and the associated chain and box blank guides 75 and 80 are individually adjusted without removing any parts from the machine.

The conveyor structure delivers the blanks successively into the path of travel of the mandrels 23, the position being determined by the stop members 22 (Figs. 4, 23 and 27) and by suitable side guides or gauges 210 (Figs. 22, 23 and 27).

The timing is such that a carton blank is delivered into position at just about the time the leading face of a mandrel 23 is immediately under the position of the box blank as represented in Fig. 4. However, the blank is, at least, partially supported by extended end portions of the side guide elements 104 and 105 as represented in broken lines in Fig. 6, and in full lines in Fig. 5.

The approaching mandrel 23, moving upwardly, comes into engagement with the central or bottom forming panel 1 of the box blank and thereby carries the box blank upwardly. The side wall panels 2 of the box blank are thereby caused to initially engage breaker rolls or rods 211 which are associated with the respective side wall folding rolls 7. The breaker rods 211 are set slightly outwardly relative to the inner faces of the folding roll 7 as shown in Figs. 4, 24 and 26.

The mounting of the breaker rods 211 and of the folding rolls 7 is best shown in Figs. 5, 23, 24 and 25. As there shown, the breaking rods 211 are provided at each end, with a laterally extending pin or leg 212 which is slidable in an open-

ing bored in a boss 213 formed integrally with a hub 214. The hub 214 is secured to the bearing boss 215 of an arm 216 which is supported on a normally fixed cross bar 217. The arm 216 is adjustably secured to the cross bar 217 by means of a screw 218 which passes through a slot in the arm 216 and is threaded into the bar 217. Adjusting screws 219 are anchored against longitudinal movement in a bar 220 which is secured at its ends to the arms 216, and said screws are threaded into the normally fixed cross bar 217 so that by turning the screws 219 the arms 216 and the folding roll 7 may be adjusted crosswise of the bar 217 or transversely of the length of the folder 7.

The folding rolls 7 are journaled for free rotation in the bearing bosses 215 of the arms 216 through the agency of suitable anti-friction bearings as shown in Fig. 25, so that the folding rolls are very freely rotatable.

The hubs 214 which carry the breaker rods 211 are provided with arms 221 which are slotted as indicated at 222, to permit the passage of clamping screws 223 through the arms and into threaded engagement with upstanding lug portions of the arms 216. By loosening the locking screws 223, the breaker rod 211 may be adjusted about the axis of the mounting screws 224 which are substantially coaxial with the roll 7, thereby permitting selective setting of the normal position of the breaker rods 211 relative to the surfaces of the respective folding rolls 7.

Compression springs 225 about the breaker rod mounting pins 212 serve to yieldingly urge the breaker rod to its innermost position which is determined by heads on the outer ends of the said pins 212 as shown in Fig. 24.

The breaker rods 211 take the initial shock of initiating downward folding of the side wall panels of the upwardly moving box blank about the corners of the mandrel which coincide with the pre-formed fold lines which separate the side wall panels 2 from the bottom panel 1. The box blank travels but a short distance upwardly after the side wall folding is initiated whereupon the folding rolls 7 engage the initially folded side wall panels to complete and perfect the folding thereof.

The side wall folding rolls 7 are preferably of a fairly soft, resilient rubber construction supported on metal shafts and the rubber portions of these rolls are crowned as clearly indicated in Figs. 5, 25 and 30. By employing crowned folding rolls 7 as indicated, the central portions of side wall panels 2 are subjected to an inward bending operation or overfolding (see Figs. 26 and 27), the mandrels being so formed as to permit this overfolding.

This inward overfolding of the side wall panels and partially counteracts the inherent resiliency of the box blank material so that when the box is completed and removed from the machine, said side walls will assume a substantially straight vertical position as represented in Fig. 33, instead of an objectionable outwardly bulging condition which has heretofore been quite common in the products of most box forming machines.

The rolls 7 are sufficiently compressible that when the leading edge portion of the mandrel passes the roll, the rolls will yield to the relatively rigid straight side flange portions 226 of the respective mandrels 23. Hence, there is no impairment of the normal squareness or straightness of the bottom corner of the box and the inward curvature imparted to the side wall is caused

to be increased progressively from the bottom edges to the top edges thereof as will be apparent from an inspection of Fig. 27.

The mandrels 23 embody the said side flange portions 226 which converge from their leading to their trailing ends and join a cross plate 227. The inside end walls 228 of the mandrel are substantially perpendicular to the cross plate 227 and they extend from the plane of the leading edges of the side flange portions 226 for a distance approximately equal to or slightly greater than the depth of the box to be formed as indicated in Fig. 27.

From the cross plate 227 there also extends rearwardly a mounting bracket arm 229 which sits against the cross bar 25 to which it is suitably fastened as by bolts or otherwise. The cross bar 25 is secured at its ends to the respective chains 24 (see Fig. 22) and the ends of said cross bar 25 are slidably mounted in slots provided in normally stationary guide bars 230. The guide bars 230 serve to guide the cross bars and the mandrels accurately through a predetermined path of travel about which the various folding devices are assembled.

The guide bars 230 on opposite sides of the machine are fixedly mounted on portions of the frame structure through the agency of suitable brackets as indicated at 231 (Fig. 2) and these guide bars extend vertically a distance corresponding substantially to the length of the vertical travel of the mandrel-carrying bars 25 which are controlled by said guides. Both the upward and downward traveling reaches of the mandrel conveyor structure are guided by slotted guide bars 230 so that during the vertical travel of the mandrels both upwardly and downwardly, they are maintained quite accurately within a predetermined path of travel. During the arcuate portions of the travel of the mandrels around the upper and lower sprockets, there is no necessity for any closely confined travel of the mandrels and hence guiding tracks, such as the tracks 230, are preferably omitted although they may be provided if desired. In this instance they are omitted.

As the mandrel and a box formation thereon emerges upwardly from between the cooperating pair of folding rolls 7, the tongues 3 at the ends of the side walls 2 are folded inwardly across the ends of the mandrel by the tuckers 9 which are carried by the rod 8. There are, of course, tuckers 9 on opposite sides of the path of travel of the mandrels and they operate substantially simultaneously so that all four tongues are folded inwardly at about the same time. This folding operation is effected with a very rapid movement just as the upper portion of the carton in formation emerges from between the forming roll 7 and immediately preceding engagement of the end wall flaps 4 with folding rolls 10 and 11.

The tuckers 9 and their respective supporting shafts or rods 8 are carried in the lower ends of arms such as indicated at 232, which are secured intermediate their ends on rock shafts 233 which are rockably mounted in brackets 234 that are fixedly mounted on the beforementioned cross bars 217 (see Figs. 23, 26 and 27).

Coiled tension springs 235 stretched between an anchoring pin carried by the lower end of each rock arm 232 and an anchoring pin carried by a portion of the respective brackets 234 serve to normally, yieldingly retract the tuckers 9 from the tongue folding position shown in Figs. 26 and 27, to initial or starting positions outwardly of

the path of travel of the mandrels as represented in Fig. 4.

Inward rocking movement of the tuckers 9 to effect folding is pneumatically effected by means of air motors, each consisting of a cylinder 236 and a piston 237 movable in said cylinder, the piston 237 having a piston rod 238 which is connected by means of a suitable hook or clevis member 239 and cross pin 240 to the arm 232. The piston 237 is actuated by compressed air emanating from a compressor 241 (Figs. 3 and 7) which is driven from the clutch controlled portion of the shaft 182 through the agency of a belt 242 which engages the driving pulley 183 on said clutch controlled portion of the shaft 182 and a similar pulley on the driving shaft of the compressor. The compressor is connected by means of a pipe line 243 to a pressure tank 244 and a valve 245 through which compressed air is delivered by means of flexible conduits 246 and 247 to the air cylinders 236 on opposite sides of the path of travel of the mandrels.

The valve 245 is automatically actuated to periodically pass compressed air into the respective air cylinders 236 and then relieve the compressed air from said cylinders, the valve being of a well-known 3-way type having a venting port connected to one of its passageways. The valve 245 is controlled by a continuously rotating cam 248 (Figs. 1b, 4, 6 and 21) which is suitably journaled for rotation in a bearing secured to a portion of the frame structure 17.

The cam is driven by means of a suitable chain drive 249 from the upper shaft 26 of the mandrel-carrying conveyor. Said cam 248 acts against a pivoted valve arm 250 to open and close the valve in properly timed relation to the travel of the mandrels as already indicated. While the permissible extent of movement of the piston within the cylinder 236 limits the rocking movement of the tuckers 9, it is preferred that the inward folding movement be checked by means of a suitable rubber or other cushion stops 251 positioned for engagement by finger extensions 252 of the rock arms 232. Such cushion stops 251 may advantageously be carried by cups or the like 253, which are horizontally adjustably mounted as best indicated in Fig. 26, in cross members 254 carried by the upper ends of the brackets 234. Adjustment of the cushion stops 251 inwardly or outwardly provides a convenient means for adjusting the limit of inward or folding movement of the tuckers 9.

The tuckers 9 may be temporarily held in their inward position as shown in Fig. 26, to cause the respectively adjacent corners of the box to travel across said tuckers, thereby to effect sharp folding of the tongues on the corner fold lines provided in the blank. For most boxes it is not necessary to employ this creasing or ironing action of the tuckers but it is available in this apparatus merely by appropriately forming or adjusting the cam 248.

As the mandrel with a box thereon passes between and emerges from the zone of operation of the tuckers 9, the end wall panels 4, 4 come into engagement with and are folded downwardly by the end folding rolls 10 and 11 (Figs. 26 and 27). There are, of course, end folding rolls 10 and 11 adjacent the opposite ends of the traveling mandrels (see Figs. 6 and 20), the rolls 10 and 11 at each end being coaxially aligned but separated from each other (Figs. 6 and 27) to permit the passage of the mandrel-carrying bars 25. These end folding rolls 10 and 11 at the opposite

ends of the mandrel serve to fold said end panels 4 downwardly into face to face engagement with the previously inturned tongues 3 whereby the adhesive areas 6 on said end wall panels come into engagement with the said tongues to adhesively bond the end panels and tongues and the box in its entirety in set-up condition.

It is desirable that the side and end wall panels be supported in their folded position for at least 10 a short time period in order to permit the adhesive material to set while the box parts are in their desired box condition. For this purpose there are provided in vertical alignment with the rolls 10, a series of pressure rolls 10a and a pair 15 of pressure rolls 10b; similarly, in vertical alignment with the folding rolls 11, there are provided a series of pressure rolls 11a and a pair of pressure rolls 11b. The sets of rolls comprising the rolls 10 and 10a are rotatably mounted in U-shaped brackets 255 and the sets of rolls comprising the rolls 11 and 11a are similarly rotatably mounted in U-shaped brackets 256 (see Figs. 6 and 22).

The brackets 255 are provided with laterally 25 extending ears 255a (Figs. 1b, 20 and 26) which are secured to brackets or arms 255b which depend from elongated hubs or sleeves 255c that are slidably mounted on a cross shaft 257 (Fig. 20).

The roll pair 10b are provided with outwardly 30 extending spindles or shafts 10c which are suitably journaled in bearings provided in arm or bracket elements 255d which are integral with and extend upwardly from as indicated in said hubs 255c (see Figs. 20 and 26).

The U-shaped brackets 256 are similarly provided with attachment flanges 256a (Figs. 1b, 22 and 27) and these are bolted respectively to arm or flange elements 256b which are formed integrally with elongated hubs 256c (Figs. 21, 27 and 40 28) that are slidably mounted on a cross shaft 258 (Figs. 27 and 28). The pairs of rolls 11b are supported in bracket portions 256d which are integral with and extend upwardly from the hubs or sleeves 256c (see Figs. 6, 21, 27 and 28) said 45 rollers 11b being supported on spindles or shafts 11c (Fig. 6) which are suitably mounted in openings in said bracket portions 256d.

It will be seen that the vertically aligned sets 50 of rolls 10, 10a and 10b and the vertically aligned sets of rolls 11, 11a and 11b are respectively mounted as units for unitary adjustment inwardly and outwardly on the cross shafts 257 and 258 respectively, whereby these roll sets are adjustable to various positions for forming boxes of 55 different sizes.

The position of these sets of rolls 10 and 11 is controlled by screw shafts 259 and 260 respectively (see Figs. 20 and 21). These screw shafts 259 and 260 are each provided with right and left-hand threads at their opposite ends, such threads 60 engaging correspondingly threaded openings in nuts 255e and 256e which are secured to the respective brackets 255b and 256b. Rotation of the screws 259 and 260 will accordingly adjust said brackets and the roll sets carried thereby, inwardly or outwardly as desired.

To firmly hold the sleeves 258c and the parts attached thereto against rocking on the shaft 258, lugs 258f (Fig. 21) are rigidly attached to the upper portions 258d as by bolts 258g, the said lugs being bored and slidably mounted on the shaft 26. The upper end portions of said lugs are split and provided with clamping bolts 258h whereby the hanger bracket may be adjusted

lengthwise of the shaft 26 and clamped in any desired operative position.

While the roller sets 10 and 11 are holding the end walls in folded position, the side walls are held in folded position by means of vertically disposed pressure plates 261 and 262 respectively (Figs. 26 and 27). These plates are supported near their lower ends by means of pins or rods 263 which are fixedly attached to the respective plates 261 and 262 and project outwardly therefrom, these projecting rods being slidably mounted in suitably bored bosses 264 formed in the respective brackets 234 (see also Fig. 20).

Coiled compression springs 265 disposed around said rods 263 between shoulders or flanged on said rods and the adjacent ends of said mounting bosses 264 serve to yieldingly urge the plates inwardly toward the path of travel of the mandrels to the extent permitted by the headed outer ends of said pins 263 as best shown in Fig. 27. The lower end portions of these pressure plates 261 and 262 are closely adjacent the folding rolls 7 so that they receive the box immediately upon emergence thereof from between said rolls. Under this circumstance it is not necessary to flare the receiving end portions of said pressure plates although this may be done if desired.

The said pressure plates are similarly yieldingly supported near their upper ends by means of outwardly extending rods 266 which are rigid with the respective pressure plates and slidably in tubular members 267. Coiled compression springs 268 between the ends of said tubular members 267 and shoulders or flanges on the rods 266 serve to yieldingly urge the pressure plates inwardly against the boxes passing between said plates. The tubular members 267 are axially, adjustably mounted in bearing brackets 269 and 270 respectively, the bracket 269 extending upwardly from the before-mentioned cross shaft or rod 257, and the bracket 270 depending from the cross shaft 26 (see Figs. 20, 21, 26 and 27).

The brackets 269 and 270 are each provided with a pair of openings which slidably receive a pair of said tubular members 267, and clamping bars 271 are provided for locking the respective tubular members in the desired adjusted position. Clamping screws 272 are provided for tightening the clamping bars 271 against the tubes 267. The pressure plates 261 and 262 are, in effect, floatingly mounted so that they may follow any slight deviations in the path of travel of the respectively engaged side walls of the boxes.

In order to attain an extended time period during which the adhesively united end walls and tongues are supported in face to face engagement, the holding effect of the roll sets 10 and 11 is continued during the arcuate travel of the bosses from the ascending reach of the mandrel-carrying conveyor to the descending reach thereof. Such holding means comprises, in this instance, substantially semi-circular inner and outer end holding plates 273 and 274, respectively, adjacent the path of travel of the opposite ends of the mandrels. The inner holding plates 273 are supported by means of a plurality of outwardly projecting headed pins 275 which are rigid with the respective plates 273 and slidably in openings provided in upwardly and laterally extending arm-like extensions 276 of aforesaid upper bracket portions 256d (see Figs. 1b and 21). The outer holding plates 274 are similarly supported by means of outwardly extending headed pins 277 which are rigid with the respective plates and slidably mounted in approximately

arched brackets 278 which are rigidly secured to ears 279 which project upwardly from the pressure roller carrying brackets 255d, and to ears 280 which are integral with and extend upwardly from sleeves 281 which are slidably mounted on a cross shaft 282 (see Figs. 2 and 6) which, like the shaft 257, is mounted in suitable openings in the frame structure 17. A screw shaft 283 having right-hand and left-hand threaded portions respectively, engaging correspondingly tapped openings in the brackets 280 or nuts attached thereto is rotatable to effect inward and outward adjustment of said brackets 280 and sleeves 281 along the shaft 282, the pressure plate 274 being also thereby adjusted. Suitable compression springs 284 (Fig. 21) are provided on the pins 275 and 277, to yieldingly urge said pressure plates inwardly or toward the path of travel of the mandrels and boxes formed thereon.

Referring now to Fig. 1b, it will be seen that the screw shafts 259, 260 and 283 are respectively provided with sprocket wheels 285, 286 and 287 for engagement by an endless chain 288 whereby rotation of any one of the screw shafts will be imparted to each of the other of said screw shafts, thereby to effect simultaneous and uniform adjustment of the parts which are effected by said screw shafts as already explained.

The screw shaft 260 is, in this instance, provided with a squared end portion 260a (Fig. 21) whereby a wrench or hand wheel may be applied to that shaft for manually turning the same when it is desired to adjust the positions of the related parts. As shown in Fig. 1b, the chain 288 is also guided around an idler sprocket 289, this being primarily for the purpose of dodging the chain out of the way of certain other parts in the structure which will presently be described. The idler sprocket 289 may, however, be adjustably mounted on the frame structure so as to permit adjustment of the tautness of the chain 288, thereby to provide some control against excessive lost motion in the chain drive transmission between the said screw shafts.

As a mandrel carries a formed box from the discharge end of the semi-circular upper loop-end pressure plates 273 and 274, the glued ends of the box are subjected to the further pressure of pairs of pressure rolls 290 and 291 (see Figs. 4 and 6). The pairs of rolls 290 are provided with extended pivot shafts such as indicated at 292 (Fig. 27) and these shafts are suitably mounted in the brackets 256d. The outer roll pairs 291 are similarly rotatably supported by shafts mounted in bracket portions 284 which depend from said sleeves 281 (Figs. 4 and 6).

Extending downwardly from the lowermost of the rolls 290 and 291 are pairs of guide plates 293 and 294 (Figs. 4 and 22) which continue the holding effect of the preceding pressure plates and rolls while the box is stripped from the descending mandrel. The pressure plates 293 are supported by attachment either directly or through other parts to the transversely adjustably mounted bracket parts 256b (see Figs. 22 and 28) and the pressure plates 294 are supported by attachment either directly or through other parts to the transversely adjustably mounted brackets 284. The holding plates 293 and 294 are spaced from each other to permit passage of the mandrel-carrying bars 25 between such plates, this being also true of the pressure roll pairs 290 and 291 and of the inner and outer arcuate pressure plates 273 and 274.

For stripping the boxes from the mandrels

during their descent between the opposed pressure plate pairs 293 and 294, there are provided pairs of endless chains 295 and 296 which are provided with box stripping members 297 and 298 respectively. These stripping members are of three-fingered form, the fingers extending through slots 299 and 300 respectively, in said pressure plates 293 and 294. The inner ends of the stripping fingers are operative to engage the then upper free edges of the boxes on the mandrels and said chains 295 and 296 are propelled at a higher speed than the travel of the mandrel so that said fingers will push the box off the mandrel while the mandrel continues its normal rate of travel. The end walls of the mandrel are preferably notched as indicated at 301 to receive the stripping fingers so that adequate engagement between the stripping fingers and box edges may be assured.

The stripping chains 295 are carried by upper and lower sprockets 302 and 303 respectively. The upper sprockets 302 are mounted on shafts 304 which are journaled in suitable bearing bosses 305 which are formed integral with bracket plates 306 which are suitably bolted or otherwise secured to the transversely adjustable brackets 256b. The lower sprockets 303 are similarly rotatably mounted in bearing elements 307 which are vertically adjustably slidably mounted on said bracket plates 306 so that the tautness of the chains 295 may be readily adjusted as required. To facilitate adjustment of the lower sprockets 303, adjusting screws 308 are threaded through lugs 309 on the bracket plates 306, these screws engaging end portions of said bearing brackets 307 to urge the same away from the bearing bosses 305 in which the upper sprockets 302 are mounted for rotation. Suitable locking screws are provided as shown in Fig. 28 passing through the bearing members 307 and into the bracket plates 306 for locking said lower bearing members in selected position of adjustment.

The outer chain pairs 296 are similarly supported by upper and lower sprockets 310 and 311 respectively (Figs. 1b, 2 and 22), the upper sprockets 310 being supported in bearing bosses 312 formed integrally with or suitably attached to the transversely adjustable bracket members 284. The lower sprockets 311 are supported through the agency of bearing brackets 313 which are the counterpart of the brackets 307 (Fig. 28) and vertically adjustably mounted on depending bracket-like extension portions 314 (Figs. 1b and 2) of the upper bearing bracket members 312. The upper sprockets 302 and 310 of the inner and outer stripping chains have their mounting shafts extended and respectively provided with pairs of bevel gears 315 and 316 (Fig. 22) which respectively mesh with complementary bevel gear pairs 317 and 318. The bevel gear pair 317 is non-rotatably but longitudinally slidably mounted on a cross shaft 319 which is journaled in suitable bearings carried by the transversely adjustable bracket plates 306. Similarly, the bevel gears 318 are non-rotatably but longitudinally adjustably slidably mounted on a transverse shaft 320 which is journaled for rotation in suitable bearings carried by the transversely adjustable elements 284. The shafts 319 and 320 are anchored against longitudinal movement relative to the main frame structure by being passed through eye bolts 321 depending from a part of the frame structure (see Figs. 2 and 22), suitable anchoring nuts or collars 322 being provided on the respective shafts on opposite sides of said eye bolts. The shafts 319 and 320

are continuously driven at the required speed by means of a chain 323 which engages sprockets 324 on the shafts 319 and 320, and a sprocket 325 on the driven shaft 196 (see Figs. 2 and 22).

As indicated in Fig. 4, the carton or box stripped from a mandrel 23 drops downwardly and is received on the discharge conveyor 28 which carries the finished box to whatever receiving means may be provided for that purpose.

The box forming section of the described apparatus, like the blank conveying section, is readily adjustable to form boxes of a considerable range of sizes. To change the box forming section to produce a different size, the mandrels 23 are first replaced with another set of mandrels of the desired size, this being readily accomplished by detaching the mandrels from the mandrel-carrying bars 25. As indicated in Fig. 2, this is accomplished by removing a single bolt 326 whereupon the mandrel may be withdrawn from a pair of dowel pins 327 which are carried by the carrier bar 25 and which pass through openings provided for that purpose in the mandrel mounting arm 229 to prevent rocking of the mandrel about the axis of the bolt 326. Mandrels of other sizes are, of course, appropriately drilled to fit the dowel pins 327 and to receive the attachment bolt 326.

With the mandrels replaced, and assuming that a smaller mandrel has been substituted, the screw shaft 260 is turned by means of a wrench or hand wheel applied to the squared end 260a of the screw shaft. Rotation of this shaft is transmitted to the screw shafts 259 and 283 by means of the chain 288 and sprockets on the said shafts (see Fig. 1b) so that the three shafts 259, 260 and 283 are simultaneously rotated in the same direction. These shafts are, of course, of like construction and each of these shafts has right and left-hand threading which engages threaded portions of the structures which carry the end wall folding rolls and pressure plates and the chain devices which strip the boxes from the mandrels. These parts are, of course, slidably supported on the stationary cross shafts 257, 258 and 282, and on the cross shaft 26 on which the mandrel conveying chains are supported.

During such adjustment of the end wall engaging devices, the bevel gears 317 and 318 slide on the shafts 319 and 320 to which they are splined as indicated in Fig. 22. The intermeshing bevel gears 315 and 317 and the intermeshing bevel gears 316 and 318 maintain their driving engagement during this adjustment, suitable provision being made as indicated in Fig. 22 to cause the gears 317 and 318 to follow the gears 315 and 316 respectively.

In connection with this adjustment of the end wall folding and pressure devices toward and from each other, the tuckers 9 are also adjusted toward or from each other as required. The tuckers are individually adjusted. Each tucker member 9 is in the form of a thin metal plate which is secured to a mounting block 339 (see Figs. 23 and 27), the said mounting block being split and provided with a clamping screw 340 whereby the block 339 may be releasably locked in selected position on the tucker bar 8. To adjust the tuckers, the locking screws 340 are loosened and the mounting blocks 339 slid along the shaft to the desired position and the screws again tightened. Incident to this adjustability of the tuckers lengthwise of the carrying rods 8, the tuckers may also be adjusted circumferential-

ly of the rods if desired. In Fig. 23, the tuckers are shown in full lines at their outermost positions, and in broken lines at inwardly adjusted positions.

Incident to changes in the setting of the end wall folders and pressure plates, it may also be desirable to adjust the positions of the side guides 210. These side guides are carried by split mounting blocks 341 (see Figs. 23 and 27) which are adjustably mounted on a cross rod 342, the latter being supported by hangers 343 which depend from the ends of the cross bars 217 (see also Fig. 21). By releasing the clamping blocks 341 the side guides 210 may, of course, be adjusted toward or from each other along the supporting rod 342.

The stops 22 are also mounted on the cross rod 342 so as to be adjustable toward and from each other or crosswise of the machine, so as to be adapted to engage selected portions of the leading edges of the box blanks as they are delivered into forming position in the machine. As shown in Figs. 23 and 27, said stop members 22 are secured to sliders 344 which slidably fit elongated track members 345. These track members 345 extend lengthwise of the direction of travel of the box blanks during their delivery to the forming section of the machine, and said tracks are secured to suitable clamping blocks 346 which are adjustably secured to the said cross rod 342. By releasing the clamping blocks 346 said blocks and the stops carried thereby may be adjusted to the desired positions along the length of the supporting rod 342 and thereby locked. Similarly, the sliders 344 may be adjusted along the lengths of the tracks 345 to adjust the positions of the stops 22 at the desired distance from the path of travel of the mandrel. Suitable set screws indicated at 347, are provided for locking the sliders in the desired position along the tracks 345.

The mandrel conveying chains remain in relatively fixed position since they are in effect, interconnected by the mandrel carrying bars 25 which are not changed. Since the mandrel carrying bars 25 are not changed, it will be understood that the vertical track members 230 which guide said bars during their vertical travel are not changed but are fixedly mounted on conveniently accessible parts of the frame 17 either directly or through the agency of suitable brackets for that purpose as shown in Fig. 2.

In addition to adjusting the end wall folding roll sets and pressure plates toward each other, the side wall folders comprising the breaker rods 211 and folding rolls 7 and the side wall pressure plates 261 and 262 (Figs. 26 and 27), are adjusted toward or from each other to fit the changed mandrels.

As already explained, the side wall breaker rods 211 and folding rolls 7 together with the tongue tucking members 9, are mounted on cross rods 217 (see Figs. 5, 22, 26 and 27). These cross bars 217 are secured at their ends to endwise extending brackets 328, 328 which have bored and tapped end bosses 329 threadedly engaging right and left-hand threaded portions of longitudinally extending screw shafts 330, 330. These screw shafts 330 are journaled for rotation in suitable eye bolt bearings 331 and 332 at the opposite ends of the screws, and said screws are locked against endwise shifting by suitable collars or nuts secured to the screw shafts outside of the respective bearings 331 and 332. The screw shafts 330, 330 are extended endwise to the delivery end of the machine by extension rods 333 which are

suitably coupled to the screw shafts and rotatably supported at their opposite ends by means of eye bolt bearings such as indicated at 334 (Figs. 22 and 1b).

The shaft extensions 333 are interconnected by means of an endless chain 335 which engages sprockets 336 secured to said shaft extensions so that rotation of one of the shaft extensions will be transmitted to the other to the end that both of the screw shafts 330 will be simultaneously rotated. One of the screw shaft extensions is provided with a squared end portion 333a for the application of a wrench or hand wheel whereby the screw shafts 330 may be rotated to correspondingly adjust the brackets 328 and the supporting bars 217 toward or from each other, whereby said side wall breaker rods, folding rolls and said tongue tuckers will be adjusted toward and from each other. In Figs. 5, 22, 26 and 27, the folding rolls 7 and associated parts are shown in nearly their maximum spread position for forming a box of the largest size the machine is designed to handle. From the illustrated position, adjustment of said folding rolls 7 is mainly toward each other to position for forming smaller or narrower boxes. Small adjustments of the folding rolls 7 of course, made by adjusting the arms 216 crosswise of the supporting bars 217 in the manner already explained.

To lock the screw shafts 330 in adjusted position, there are provided clamp locks comprising split bearing members 337 which extend upwardly from a suitable supporting bracket carried by the frame structure 17 (see Figs. 5 and 23), these split bearings being adapted to be clamped tight on the shafts 330 by means of clamping screws 338.

In connecting with adjustment of the side wall folding rolls 7 toward or from each other, the lower end portions of the pressure plates 261 and 262 (see Figs. 26 and 27) are correspondingly adjusted toward or from each other since said lower portions are connected to the brackets 234 which are mounted on the cross bars 217. The upper end portions of said pressure plates 261 and 262 are manually adjusted inwardly or outwardly by loosening the locking screws 272 and manually adjusting the guides 267 inwardly or outwardly as required. As shown in Figs. 26 and 27, the pressure plates are located very nearly at their extreme outer positions so that but little further outward adjustment is possible from the position shown. From the setting shown, the pressure plates 261 and 262 are adjustable toward each other to the extent of the lengths of the portions of the guide tubes 267 which project outwardly beyond the respective supporting members 269 and 270. However, in the event that the end folding rolls 10 and 11 are also to be adjusted toward each other to fold smaller boxes, the pressure plates 261 and 262 may be readily removed and replaced by narrower plates which will fit between the opposed sets of folding rolls 10 and 11 (see Fig. 6). To that end, the outer ends of the members 263 and 267 are provided with suitable wrench receiving sockets whereby said members 263 and 267 may be unscrewed to permit removal of the plates 261 and 262 and replacement thereof as aforesaid.

On the descending side of the mandrel structure there are no parts which engage the side walls of the boxes. The stripper chains are so located that the stripping fingers 301 engage central portions of the respective end walls and are thereby operative in the position shown for a very

wide range of box sizes. In some instances, for making exceptionally narrow boxes, stripping may be effected by engagement of only the innermost fingers of the strippers with the end walls of the boxes, the other fingers remaining idle.

By reference to Figs. 2 and 21, it will be seen that the chains 24 of the mandrel carrying structure are guided by sprockets 348 which are rotatably mounted on the upper shaft 26, suitable collars secured to the shaft being provided for maintaining the sprockets in proper position on the said shaft. Sprockets 349 are rigidly secured to the lower shaft 27 so that rotation imparted to said lower shaft 27 will drive both of the mandrel conveyor chains. The mandrel conveyor chains are driven by means of a chain 350 (see Figs. 1b and 2) which engages a driving sprocket 351 on the driven shaft 196 and a sprocket 352 on the shaft 27. An idler sprocket 353 is provided for controlling the tautness of the chain 350, said idler being supported by an arm 354 which is mounted for adjustment by a pivot 355 suitably supported on a bracket part of the frame structure and adapted to be locked in adjusted position by suitable clamping or set screw means.

From the foregoing explanation, it will be seen that the described box forming machine is very flexible in respect of the range of box sizes which may be produced on the machine, and that changing of the structure to produce different sizes of boxes may be very expeditiously effected. A competent mechanic can effect necessary adjustments to change the machine from the production of one size of box to another size in a matter of about 20 minutes. This is advantageous especially for manufacturers who produce various types of merchandise in a single line of equipment, and who also package such merchandise in various sizes of cartons or boxes.

For example, manufacturers of candy bars and similar packages frequently adjust the size of the bars being produced in accordance with the cost of production of the bar so as to permit the sale of the product at a fixed price notwithstanding fairly substantial changes in the cost of production. For manufacturers who follow that practice, the described packaging machine is highly advantageous because of the facility with which it may be adjusted to the forming of various sizes of boxes.

The apparatus is also highly advantageous because it is a continuous motion type of mechanism capable of operating at speeds to produce boxes at rates varying from around 30 or less per minute up to more than 100 per minute. Adjustment of the speed of operation is facilitated in the described mechanism by mounting the driving motor 179 on a pair of triangular platform forming brackets 356 which are pivotally mounted at their lower ends as indicated at 357, on the supporting frame structure. These platform members have upwardly extending arm portions 358 and the upper ends of these arm extensions are interconnected by means of a roller 359.

This roller 359 has a threaded opening extending therethrough and said opening is engaged by a screw 360 which is rotatably supported but anchored against axial movement in a suitable bearing 361 and said screw is provided with a hand wheel 362 whereby it may conveniently be rotated. Rotation of the screw 360 serves to rock the platform members 356 about the axis of the pivots 357 thereby to move the motor 179 toward or from the axis of the main drive shaft 182.

The belt 180 is driven by engagement with an

automatically variable diameter pulley 363 which is mounted on the shaft of the driving member 179 so that adjustment of the motor toward or from the axis of the drive shaft 182 automatically results in adjustment of the effective diameter of said pulley 363 and corresponding adjustment of the speed at which the main drive shaft 182 is driven. The pulley 363 is of well-known construction and is commercially available wherefor the details thereof are not shown.

Because the end wall structures of the boxes are held under pressure during the vertical upward travel of the mandrels during the arcuate travel thereof about the axis of the upper shaft 26, ample time is provided for setting of the adhesive. To accelerate setting of certain types of adhesive, the pressure plates or the pressure rollers which engage the end walls, or both of them, may be heated by means of electrical heating coils or otherwise, and for the purpose of accelerating the setting of thermoplastic adhesives these plates may be air, water or otherwise glued. However, for most purposes, temperature treatment of the pressure devices is not required.

By employing the pneumatic means 236 for actuating the tuckers and the flexible hoses 247 for connecting such actuating means to the control valves, adjustment of tucker devices inwardly or outwardly may be effected without regard to connections for actuating said tuckers. Hence, simplification is attained in this respect by the use of pneumatic mechanism instead of mechanical linkage.

Referring now to Figs. 34 to 43 of the drawings, there is illustrated a modified form of box and a modification of the apparatus already described to adapt the same to production of the box of Figs. 34 to 36.

The box shown in Fig. 36 comprises a bottom panel 364 and two-ply side and end walls as distinguished from the single ply side and end walls of the carton structure shown in Fig. 33. The modified carton also has a two-ply lid formed integrally with one of the side walls.

As shown in Fig. 34, the bottom panel 364 is provided with endwise extending panels 365 and 366 on its opposite ends. The end panels 366 are adapted to be folded over the adjacent end panels 365 to form two-ply end walls for the container of Fig. 36. One of the side walls is formed from

side wall panels 367 and 368, the latter being refolded into face to face relation to the panel 367 and adhesively united thereto and the two panels 367 and 368 being foldable to wall forming relation to the bottom panel 364. From the opposite side of the bottom panel 364 there extend panels 369, 370, 371 and 372, the panels 370 and 371 being of like size as are also the panels 369 and 372. These panels are integral with the bottom panel 364 and are folded into the face to face relation

shown in Fig. 34 so that when the side wall panel pair 369 and 372 is folded upwardly from the bottom panel 364, such side wall panel pair will form a two-ply side or back wall from which the lid panels 370 and 371 extend upwardly.

Tongues 373 extend endwise from the opposite ends of the outer plies 367 and 369 of the front and back side of walls respectively.

The box blank is preferably supplied by the manufacturer of the blanks in the form illustrated in Fig. 34, that is to say, with the front wall panel ply 368 folded over and united to the inside of the outer ply 367 and with the lid and back wall inner plies 371 and 372 folded over the inside of the lid and back wall outer plies 370 and 369 respectively.

For certain purposes, not necessary to consider here, it is preferable that the inner ply 372 of the back wall panel be left unattached to the face of the outer ply 369 of the back wall. The inner ply 371 of the lid is, however, preferably adhesively united in face to face relation to the outer ply 370 of the lid.

A blank in the condition illustrated in Fig. 34, is positioned in the apparatus by stops and guides appropriately positioned as already explained. The arrangement is such that the front side wall panels 367 and 368 are at the leading edge of the blank as it enters the forming position in which it is illustrated in Fig. 37, the lid panels 370 and 371 being at the trailing end of the blank. The various panels are, of course, foldably connected to the bottom panel and to each other along suitably creased or scored or otherwise formed fold lines to facilitate folding of the panels to box forming position.

Initial folding is effected substantially as before by means of the breaker rolls 211 and folding rolls 7 in cooperation with a mandrel designated in its entirety by the reference numeral 374, this mandrel being different than the mandrel 23 but carried by and propelled through its path of travel by a mandrel carrying bar 375 which is substantially the same as the mandrel carrier 25, and the same chains indicated at 24.

The leading end of the mandrel 374 substantially corresponds in area to the area of the inside face of the bottom panel 364 and in the course of the upward movement of the mandrel it engages said bottom panel 364 to move the carton upwardly between the breaker rolls 211 and folding rolls 7 to thereby effect downward folding of the front wall plies 367 and 368 and the back wall plies 372 and 369 together with the lid plies 370 and 371. The lid plies 370 and 371 remain in their co-planar relation to the back wall plies and are not folded relative thereto so that when the box is discharged from the machine, the lid is disposed in upstanding position as shown in Fig. 36. This relationship is also illustrated in the upper portion of Fig. 37 wherein the front wall and the back wall and lid are shown in depending relationship to the bottom panel, the box being then in inverted position.

As the box progresses upwardly beyond the initial folding rolls 7, tuckers 9 fold the tongues 373 inwardly in the same manner that said tuckers folded the tongues 3 inwardly in the first described arrangement. Thereafter, the rolls 10 and 11 operate (as before) to fold the end wall panels 365 downwardly, the continuation panels 366 remaining in their co-planar relationship to the panels 365 until acted upon by mechanisms which will presently be explained.

Inward folding of the end wall panels 366 relative to the outer end wall panels 365 is effected by means of pairs of folding fingers such as shown at 376 (Figs. 38, 39 and 40). There is a pair of these folding fingers associated with each set of rolls 10, 10a and 10b and with set of rolls 11, 11a and 11b, these fingers and operating mechanisms therefore, being made up in units mounted in the U-shaped brackets 255 and 256 in place of two of the rolls 10a and 11a otherwise provided in said brackets (see Figs. 38 and 42).

Each pair of fingers 376 is carried by a shaft 379 which is journalled in vertically extending bars 380 formed integral with or attached to a base plate 381 which is suitably mounted in the respective U-shaped bracket 255 and 256 (Fig. 42).

The fingers 376 of each unit, are rocked from the starting position shown in Fig. 38, to the position shown in Fig. 39 with a fast, almost snap-action while the box is being propelled upwardly on the leading end of the mandrel. This rapid folding movement of the fingers is effected by means of rack bars 377 which mesh with pinion segments 378 secured to the shaft 379 which carries said fingers.

The rack bars 377 are carried by the free outer ends of piston rods 382 which carry pistons within pneumatic cylinders 383. When the box reaches proper position for folding fingers 376 to act on the end wall panels 366, compressed air is delivered into the cylinders 383 to thereby move the pistons and racks 377 outwardly so as to effect the required folding movement of said folding fingers. Springs 384 stretched between the opposite ends of cross bars 385 carried by the respective racks 377 and the opposite ends of cross arms 386 on the upper ends of the cylinders 383 serve to retract the rack and return the folding fingers to their starting position.

The delivery of air under pressure to the pneumatic cylinders 383 is controlled by a suitable valve 387 (Fig. 43) which is opened and shut by means of a rotary cam 388. This rotary cam 388 may be on the same axis as the cam 248 and driven in properly synchronized relation thereto. The action of the folding fingers 376 is slightly subsequent to the action of the tuckers 9 but the timing is the same in each cycle so that the cam 388 may be rigid with the cam 248 if desired. In Fig. 43 the location of the cam 388 is shown in about horizontal alignment with the shaft 26 and this represents another position in which the cam 248 may also be located if desired.

The cam 388 is provided with a high point of somewhat greater dwell than the cam 248 it being preferred to hold the folding fingers 376 in their up positions as shown in Fig. 39 for a moment or two while other folding means are brought into position for continuing the folding of said end flaps 366.

The means for continuing the folding of the end flaps 366 from the partially folded position illustrated in Fig. 39 to fully folded position is best shown in Figs. 38 and 39, certain details also appearing in Figs. 37 and 41. This folding mechanism is mounted in the mandrel 374 which comprises a rigid front end frame consisting of side members 389 and crosswise extending end members 390 which rigidly unite the side members. These side members and cross members provide a rigid, substantially rectangular frame structure and the cross members are reinforced by an intermediate member 391 which is parallel to the side members but spaced from both of them (see Figs. 38, 41 and 43).

The intermediate member 391 is extended downwardly in the form of an arm 392 and the lower end of such arm portion is suitably secured to the mandrel carrying cross bar 375. End plates or cross plates 393 are suitably mounted on the cross members 390, these cross plates having their outer faces co-planar with the front end of the mandrel and extending outwardly to provide the mandrel with the required length which is substantially the same as the inside length of the box to be formed.

The opposite sides of the mandrel are provided with plates 394 and 395 which are respectively of a depth approximately corresponding to the depth of the rear wall and lid and the depth of the front wall as shown in Fig. 37. These plates 394 and 395 serve to support the folded front and

rear side walls and the lid against the pressure plates 261 and 262. The supporting plate 394 may have its extended portion reinforced and supported by means of a suitable bracket structure 394a having a base portion secured to the member 394 and an end portion attached to the arm 392 as best shown in Fig. 37.

End wall folders 396 and 397 are mounted for movement within the mandrel, the folder 396 being supported by a pair of arms 398 which are pivotally mounted at their inner ends on a cross shaft or pivot pin 399. Similarly, the folder 397 is carried by a pair of arms 400 which have their inner ends pivotally mounted on a cross shaft or pivot pin 401. The pivot pins 399 and 401 are suitably secured in the side members 389 of the mandrel structure. By reference to Figs. 38 and 39 it will be seen that the mandrel carried folding members 396 and 397 may be rocked outwardly from an initial position shown in the lower portion of Fig. 38 and upwardly through the position shown in Fig. 39 to the position shown in the upper portion of Fig. 38, thereby to engage the partially folded end wall panel 366 as shown in Fig. 39, and effect folding thereof to the fully folded position shown in the upper portion of Fig. 38. This rocking movement of the folders 396 and 397 is effected automatically as an incident to the travel of the mandrel. For this purpose there is provided lower and upper cam bars 402 and 403 respectively, these bars extending vertically in parallelism with the path of travel of the mandrel and being rigidly held in fixed position by suitable brackets such as indicated at 404, whereby the cam bars are mounted on the main frame structure of the machine.

The cams 402 and 403 are arranged to act on a roller 405 carried by one end of a rock arm 406 which is pivoted on a lug 407 extending from the mandrel carrying cross bar 375. The other end of the rock arm 406 is connected by a link 408 to the free end of an arm 409 which is one arm of a bell crank pivoted as indicated at 410 on another portion of the cross bar 375. The other arm 411 of said bell crank is connected by means of a pair of links 412 and 413 respectively to the arms 398 and 400 as indicated at 414 and 415. By examination of Fig. 38 it will be seen that as the mandrel moves upwardly, the roller 405 is carried into engagement with the shaped end portion 402a of the cam bar 402 whereby the rock arm 406 is rocked, thereby to correspondingly rock the bell crank arms 409 and 411.

As shown in the lower mandrel of Fig. 38, the cam 402a has effected retracting movement of the folders 396 and 397 so as to insure their being out of the way of the folding fingers 376 which effect initial inward folding of the end wall panels 366 and out of the way of said end wall panels to permit to be freely folded into the position shown in Fig. 39. As the mandrel progresses upwardly, the roller 405 comes into engagement with the inclined cam edge 403a of the upper cam bar 403, whereby the rock arm 406 is rocked in the other direction to thereby effect corresponding rocking of the bell crank arms 409 and 411 whereby outward swinging movement is imparted to the folders 396 and 397 to the position they are illustrated in the upper mandrel in Fig. 38. During the course of this upward swinging movement of these members 396 and 397 they come into engagement with the end wall panels 366 as shown in Fig. 39 and fold

the same upwardly and outwardly to the position in which they are illustrated in Fig. 38.

As indicated in the drawings, the end wall panels 366 are folded inwardly and upwardly around the inturned tongues 373 which have previously been folded inwardly by the tuckers 9.

During the progress of the blank from the magazine to the folding mechanism, adhesive is applied to the inside faces of the tongues and end wall panels 365 in areas represented at 373a on the tongues and areas 365a on said end wall panels 365. This application of adhesive requires appropriate modification of the adhesive applying members 20. When the blank is folded in the manner explained, the tongues 373 will become adhesively united to the outer end wall panels 365 through the agency of the adhesive areas 365a and the inner end wall panels 366 will become adhesively united to the tongues 373 through the agency of the adhesive areas 373a on the tongues.

During the further progress of the mandrels through the machine, the folders 396 and 397 remain in their expanded position as shown in the upper mandrel of Fig. 38. A spring such as indicated at 417 yielding urges the folders 396 and 397 to said expanded position after the roller 405 leaves the cam 402 whereby said inner end wall panels 366 are yielding held in engagement with the tongues thereby affording time for the adhesive to set before the normal resiliency of the stock in the box can effect unfolding of said inner panels 366.

Stripping of the box from the mandrel is effected by the same arrangement described above. To permit the strippers to function properly, the folders 396 and 397 are notched as indicated at 416.

Both of the described structures may be modified in respect of various details while retaining the principles and benefits of the invention.

I claim:

1. Box making apparatus of the class described, comprising a mandrel, means for moving said mandrel along a predetermined path of travel, means for positioning a box blank in said path of travel so as to enable said mandrel to engage and carry said blank along said path of travel, a folding roll of compressible resilient material adjacent one side of said path of travel for cooperating with a side of said mandrel to fold a portion of the box blank, said mandrel side having a substantially straight edge portion around which said portion of the box blank is folded and being recessed beyond said edge so as to permit said box blank portion to be bent inwardly beyond a normal flat wall condition to thereby cause the inherent resiliency of said portion to restore the same to a substantially flat wall condition, said folding roll being crowned to approximately conform to said recessed mandrel wall to thereby effect said inward bendings of said portion of the box blank.

2. Box making apparatus of the class described, comprising a mandrel, means for moving said mandrel along a predetermined path of travel, means for positioning a box blank in said path of travel, whereby said mandrel is operative to engage and carry said box blank along said path of travel, an opposed pair of folders positioned adjacent opposite sides of said path of travel for folding wall forming portions of said box blank into wall position over opposite side portions of said mandrel as an incident to the movement of said mandrel along said path of travel,

fluid actuated means for inwardly folding tongues which extend from the ends of one of said wall forming portions of said box blank, means for timing the operation of said tongue folding means with reference to the operation of said folders, and means supporting said pair of folders for adjustment toward and from each other to thereby adapt the apparatus to the making of boxes of various sizes.

3. Box making apparatus of the class described, comprising a mandrel, means for moving said mandrel along a predetermined path of travel, means for positioning a box blank in said path of travel, whereby said mandrel is operative to engage and carry said box blank along said path of travel, an opposed pair of folders positioned adjacent opposite sides of said path of travel for folding wall forming portions of said box blank into wall position over opposite side portions of said mandrel as an incident to the movement of said mandrel along said path of travel, fluid actuated means for inwardly folding tongues which extend from the ends of one of said wall forming portions of said box blank, means for timing the operation of said tongue folding means with reference to the movement of said mandrel, and means supporting said pair of folders for adjustment toward and from each other to thereby adapt the apparatus to the making of boxes of various sizes, said tongue folding means being mounted on the supporting means for one of said folders and adjustable therewith as aforesaid.

4. Box making apparatus of the class described, comprising a mandrel, means for moving said mandrel along a predetermined path of travel, means for positioning a box blank in said path of travel, whereby said mandrel is operative to engage and carry said box blank along said path of travel, an opposed pair of folders positioned adjacent opposite sides of said path of travel for folding wall forming portions of said box blank into wall position over opposite side portions of said mandrel as an incident to the movement of said mandrel along said path of travel, a pair of tongue folders respectively operative to fold tongues which extend from the ends of one of said wall forming portions of said box blank, a fluid operated cylinder and piston structure disposed intermediate and operatively connected to said tongue folders, means for actuating said cylinder and piston structure in predetermined timed relationship to the position of said mandrel during its blank folding movement, said tongue folders being mounted for adjustment toward and from each other, and said tongue folders and cylinder and piston structure being mounted for adjustment as a unit with the folders of one said opposed pairs of folders.

5. A box forming machine of the class described, comprising a series of interconnected mandrels, means for moving said mandrels successively through a continuous path of travel having a pair of substantially parallel straight run portions and semi-circular loop portions connecting the ends of said straight run portions, means for positioning box blanks in said path of travel adjacent the mandrel entrance end of one of said straight run portions thereof, whereby said mandrel may be caused to engage central panel portions of said blanks and to carry said blanks along said path of travel; a pair of mutually opposed folders operative as an incident to the travel of the blanks with

said mandrels into said straight run portion of said path of travel, to fold to wall position, a pair of side panels which extend from said central panels; tuckers associated with said pair of folders for folding inwardly over the ends of the mandrel, tongues which extend from the ends of the said side panels; a second pair of mutually opposed folders normal to said first mentioned pair and operative as an incident to the travel to said mandrel and blanks to fold into the overlying relation to said infolded tongues, end wall panels which also extend from said central panels; a pair of mutually opposed sets of pressure rolls associated with each of said end wall folders to hold said end wall panels in folded position during the travel of the folded blanks along the remainder of said straight run portion of the path of travel in which folding of the blanks is effected as aforesaid, a pair of mutually opposed arcuate pressure plates respectively aligned with said series of pressure rolls and disposed over opposite sides of a loop portion of said path of travel into which the folded blanks are carried by said mandrels, said arcuate plates being operative to hold said end walls folded during the travel of said folded blanks through said loop portion; a pair of mutually opposed pressing members disposed in continuation of said arcuate pressure plates, in end wall holding position over opposite portions of the other of said straight run portions into which the folded blanks are carried by said mandrel; a pair of mutually opposed devices for stripping the folded boxes from said mandrel during the travel of the boxes and mandrels through another portion of said other straight run portions; and means for receiving the boxes stripped from said mandrel and discharging said boxes from the machine.

40 6. A machine according to claim 5 wherein the mutually opposed end panel folders, pressure rolls, arcuate pressure plates, pressure members and stripping devices are mounted for adjustment toward and from each other.

45 7. A machine according to claim 5 wherein the mutually opposed end panel folders, pressure rolls, arcuate pressure plates, pressure members and stripping devices are mounted for adjustment toward and from each other, and having means for effecting such adjustment of said parts.

55 8. A machine according to claim 5 wherein the mutually opposed end panel folders, pressure rolls, arcuate pressure plates, pressure members and stripping devices are mounted for adjustment toward and from each other, and having means for effecting simultaneous, like, adjustment of said mutually opposed parts toward and from each other.

60 9. A machine according to claim 5 wherein the mutually opposed side panel folders and tuckers are mounted for adjustment toward and from each other, and wherein the mutually opposed end panel folders, pressure rolls, arcuate pressure plates, pressure members and stripping devices are mounted for adjustment toward and from each other.

70 10. A machine according to claim 5 wherein the mutually opposed side panel folders and tuckers are mounted for adjustment toward and from each other, and wherein the mutually opposed end panel folders, pressure rolls, arcuate pressure plates, pressure members and stripping devices are mounted for adjustment toward and from each other, and having means for effecting

simultaneous, like, adjustment of said mutually opposed parts toward and from each other.

11. A machine according to claim 5 wherein the mutually opposed side panel folders and tuckers are mounted for adjustment toward and from each other, and wherein the mutually opposed end panel folders, pressure rolls, arcuate pressure plates, pressure members and stripping devices are mounted for adjustment toward and from each other, and having means for effecting such adjustment of said parts, and a pair of mutually opposed side panel pressure plates operative to hold said side panel portions in folded position after said side panel portions clear the folders which effect folding of said portions, said side panel pressure plates being also mounted for adjustment toward and from each other and also so as to be readily removable and replaceable with other sizes thereof.

12. A box making machine comprising a pair of endless chains, rotatably mounted sprockets arranged to support said chains for continuous travel in elongated oval paths, the sprockets for one chain being coaxial with those for the other and being spaced axially therefrom, a plurality of cross bars connecting said chains for unitary movement, mandrels mounted on said cross bars in normal relation thereto and projecting beyond both sides thereof, folding devices arranged around the path of travel of said mandrels for folding box blanks around said mandrels as an incident to the travel of the latter between said folding devices, said folding devices comprising mutually opposed pairs of folders disposed adjacent the path of travel of the sides of the mandrel which are normal to said cross bars, the folders of each pair being respectively located on opposite sides of the path of travel of said cross bars, mutually opposed pairs of pressure applying devices also disposed adjacent the path of travel of said sides of the mandrel which are normal to said cross bars so as to be operative to hold folded the box blank portions which are folded by said folding devices against said normal mandrel sides, each pair of said pressure applying devices comprising inner and outer, co-planar arcuate plates respectively disposed inside and outside of the path of travel of said cross bars around one of the round ends of said elongated oval path of travel, and means for mounting said pairs of arcuate plates and the corresponding opposed folders for adjustment toward and from each other.

13. Box making apparatus of the class described, comprising a mandrel, means for moving said mandrel along a predetermined path of travel, means for positioning a box blank in said path of travel, whereby said mandrel is operative to engage and carry said box blank along said path of travel, an opposed pair of folders positioned adjacent opposite sides of said path of travel for folding wall forming portions of said box blank into wall position over opposite side portions of said mandrel as an incident to the movement of said mandrel along said path of travel, a second folder operative to engage and fold inwardly across the trailing end of said mandrel, an inner wall panel portion which extends from one of the aforesaid folded wall portions, means for actuating said second folder, means carried by said mandrel for engaging said inwardly folded inner wall panel and folding the same into substantially parallel relation to said folded wall portion, and means for actuating said mandrel carried folder.

14. Box making apparatus of the class described, comprising a mandrel, means for moving said

mandrel along a predetermined path of travel, means for positioning a box blank in said path of travel, whereby said mandrel is operative to engage and carry said box blank along said path of travel, an opposed pair of folders positioned adjacent opposite sides of said path of travel for folding wall forming portions of said box blank into wall position over opposite side portions of said mandrel as an incident to the movement of said mandrel along said path of travel, a second folder operative to engage and fold inwardly across the trailing end of said mandrel, an inner wall panel portion which extends from one of the aforesaid folded wall portions, fluid operated means for actuating said second folder, means carried by said mandrel for engaging said inwardly folded inner wall panel and folding the same into substantially parallel relation to said folded wall portion, and means for actuating said mandrel carried folder.

15. Box making apparatus of the class described, comprising a mandrel, means for moving said mandrel along a predetermined path of travel, means for positioning a box blank in said path of travel, whereby said mandrel is operative to engage and carry said box blank along said path of travel, an opposed pair of folders positioned adjacent opposite sides of said path of travel for folding wall forming portions of said box blank into wall position over opposite side portions of said mandrel as an incident to the movement of said mandrel along said path of travel, a second folder operative to engage and fold inwardly across the trailing end of said mandrel, an inner wall panel portion which extends from one of the aforesaid folded wall portions, means for actuating said second folder, means carried by said mandrel for engaging said inwardly folded inner wall panel and folding the same into substantially parallel relation to said folded wall portion, and means operated as an incident to the travel of said mandrel for actuating said mandrel carried folder.

16. Box making apparatus of the class described, comprising a mandrel, means for moving said mandrel along a predetermined path of travel, means for positioning a box blank in said path of travel, whereby said mandrel is operative to engage and carry said box blank along said path of travel, an opposed pair of folders positioned adjacent opposite sides of said path of travel for folding side wall forming portions of said box blank into wall position over opposite side portions of said mandrel as an incident to the movement of said mandrel along said path of travel, means for inwardly folding tongues which extend from the ends of said wall forming portions of said box blank, another pair of mutually opposed folders normal to said first mentioned folders, for folding a pair of end wall panel portions of said blank to wall position on the adjacent sides of said mandrel, a pair of auxiliary folders respectively associated with said end wall folders and operative to fold inwardly across the trailing end of said mandrel, an inner end wall panel portion of said blank, means for actuating said auxiliary folders, a pair of folders carried by said mandrel and operative to fold said inwardly folded inner wall panels into inwardly overlying relation to said infolded tongues, and means for actuating said mandrel carried folders.

17. Apparatus according to claim 16 wherein the means for actuating the mandrel-carried folders comprises a stationary cam member, and operating linkage carried by said mandrel, connected to said folders and having a member en-

gageable with said cam as an incident to the travel of said mandrel.

18. Apparatus according to claim 16 wherein the means for actuating the mandrel carried folders comprises a stationary cam, operating linkage carried by said mandrel and connected to said folders and having a member adapted to engage said cam so as to move said folders to open or starting position, and yieldable means for moving said folders in folding direction and yieldingly holding the same in position to maintain said inner wall panel in fully folded position.

19. A box-making machine comprising a pair of endless chains, rotatably mounted sprockets arranged to support said chains for continuous travel in elongated oval paths, the sprockets for one chain being coaxial with those for the other and being spaced axially therefrom, a plurality of cross bars connecting said chains for unitary movement, mandrels mounted on said cross bars in normal relation thereto and projecting beyond both sides thereof, folding devices arranged around the path of travel of said mandrels for folding box blanks around said mandrels as an incident to the travel of the latter between said folding devices, said folding devices comprising mutually opposed pairs of folders disposed adjacent the path of travel of the sides of the mandrel which are normal to said cross bars, the folders of each pair being respectively located on opposite sides of the path of travel of said cross bars, mutually opposed pairs of pressure applying devices also disposed adjacent the path of travel of said sides of the mandrel which are normal to said cross bars so as to be operative to hold folded the box blank portions which are folded by said folding devices against said normal mandrel sides, each pair of said pressure applying devices comprising inner and outer, coplanar arcuate plates respectively disposed inside and outside of the path of travel of said cross bars around one of the round ends of said elongated oval path of travel.

20. Box-making apparatus of the class described comprising a mandrel, means for moving said mandrel along a predetermined path of travel, means for positioning a box blank in said path of travel so as to enable said mandrel to engage and carry said box blank along said path of travel, two mutually opposed pairs of wall folders positioned adjacent said path of travel in relatively offset relation to each other for successively folding opposed pairs of wall forming portions of said box blank into wall position over opposite side portions of said mandrel as an incident to the movement of said mandrel along said path of travel, a pair of tongue folders movable inwardly and outwardly relative to said path of travel for respectively effecting inward folding of tongues which extend from the ends of one opposed pair of said wall forming portions of said box blank; means for actuating said tongue folders intermediate the successive folding operations effected by said pairs of folders, and means for supporting said pairs of wall folders for adjustment toward and from each other to thereby adapt the apparatus to the making of boxes of various sizes, said tongue folders being respectively mounted on the supporting means for one of said pairs of wall folders and adjustable therewith as aforesaid.

21. Box-making apparatus of the class described comprising a mandrel which travels along a predetermined path to engage and move box blanks through folding mechanism, a conveyor

structure comprising an endless conveyor chain having a lug for engaging the box blanks to effect delivery thereof successively into predetermined position across the path of travel of said mandrel when the latter is in a predetermined position in its path of travel, said conveyor structure being mounted for adjustment in its normal plane of operation in the direction of travel of said conveyor and reversely thereof respectively toward and from said mandrel path of travel so as to be adapted to deliver as aforesaid, box blanks of various sizes in the direction of conveyor travel, driving means interconnecting said mandrel and said conveyor for synchronized travel so as to cause said conveyor to deliver box blanks as aforesaid, and means for locking said conveyor chain and box blank engaging lug against shifting independently of movement of the conveyor structure during adjustment thereof toward and from said mandrel path, thereby to maintain said synchronized relationship between said conveyor and its box blank engaging lug with said mandrel in all positions of adjustment of the conveyor.

22. Box-making apparatus of the class described comprising a mandrel which travels along a predetermined path to engage and move box blanks through folding mechanism, a conveyor structure comprising an endless conveyor chain having a lug for engaging the box blanks to effect delivery thereof successively into predetermined position across the path of travel of said mandrel when the latter is in a predetermined position in its path of travel, said conveyor structure being mounted for adjustment in its normal plane of operation in the direction of travel of said conveyor and reversely thereof respectively toward and from said mandrel path of travel so as to be adapted to deliver as aforesaid, box blanks of various sizes in the direction of conveyor travel, a drive chain connected to said conveyor and operative to drive the same in such timed relation to the travel of said mandrel as to cause said conveyor to deliver box blanks as aforesaid, an idler guiding said drive chain through an offset in its path of travel, said idler being mounted for adjustment so as to be adapted to adjust the extent of said offset to thereby permit shortening and lengthening of the effective length of said driving chain to enable the same to drive said conveyor in various positions of adjustment thereof, and means for locking said conveyor chain and box blank engaging lug against shifting independently of movement of the conveyor structure during adjustment thereof toward and from said mandrel path, thereby to maintain said timed relationship of said conveyor and its box blank engaging lug with said mandrel in all positions of adjustment of the conveyor.

CHARLES E. PALMER
